CABINET CONSTRUCTION

Henry S. Carlson, West Orange, N. J., assignor to
Thomas A. Edison, Incorporated, West Orange,
N. J., a corporation of New Jersey

Original application October 15, 1938, Serial No.
235,213. Divided and this application April 1,
1941, Serial No. 386,225

9 Claims. (Cl. 312—191)

The invention described in this application—which is a division of my copending application, Serial No. 235,213, filed October 15, 1938, which has become Patent No. 2,289,408, dated July 14, 1942 and entitled "Phonographs"—relates to cabinets and especially to cabinets for phonographs of the commercial type.

When a commercial phonograph, or dictating machine, is made small and completely enclosed by a cabinet closely fitting the phonograph for the purpose of rendering the phonograph readily portable and suitable for desk use, the ease of operation of the phonograph may be impaired unless the phonograph and cabinet are carefully designed and well adapted to each other.

One of the difficulties encountered with a cabinet of the type just mentioned lies in rendering the phonograph accessible for convenient operation with the use of a closure means which will be compactly disposed in relation to the cabinet when the closure means is in open position. This difficulty will be readily understood in the case of the dictating machine which uses records of cylindrical form, as here the machine needs to be exposed to the front and/or top to permit access to its controls, and also to the side to permit the mounting and removal of a record onto and from the machine. This difficulty in suitably exposing the machine for operation, while yet maintaining a compact cabinet arrangement, has been overcome by means of separate closures at the different sides of the machine to which access is to be had. These closures are, however, interconnected for simultaneous operation to permit a complete opening and closing of the cabinet by a single operation. An object of this invention is to provide an improved means for interconnecting such closures.

It is another object to provide a continuous connection between such closures to insure a positive opening and closing of one upon an opening and closing of the other, and further to accomplish this result by simple and easily operable means.

In the cabinet herein shown it will be seen that the two closures are pivoted about different axes and that they are coupled together in a positive and simple manner through the medium of a sliding pivot.

It is accordingly a feature of my invention to employ a sliding pivotal connection between two closures having differently directed paths of movement.

Still other objects and features of my invention will more fully appear from the following description and the appended claims.

In the description of my invention reference is had to the accompanying drawing, of which:

Figure 1 is a side elevational view of a phonograph structure embodying my invention and showing the closures of the cabinet in open position, parts of the cabinet being broken away for the better illustration of details of the invention;

Figure 2 is another side elevational view, similar to that of Figure 1, fractionally showing the cabinet in closed condition;

10 Figure 3 is a partial sectional view of the structure of Figure 2 taken substantially along the line 3—3 of that figure; and

15 Figure 4 is a view of the side closure for the cabinet as it appears, in plan, when it is in the position it occupies in Figure 2.

Reference being had to the figures, particularly Figs. 1 and 2, there will be seen a cabinet 1 closely fitting a phonograph of the type commonly used for the recordation and reproduction of dictation. The lower portion 2 of the cabinet, comprising substantially the lower half thereof, is rectangularly shaped and preferably formed, as by casting, in an integral piece. Supported by the lower portion 2 is a base plate 3 hinged to the rearward wall 4 of the portion 2 and resting on a stud 5 provided on the forward wall 6 of the portion 2. The plate 3 has left and right upright standards of which the right standard appears as 7; these standards carry 20 the front and back longitudinal rods 8 and 9 on which there is slidably mounted a carriage 10. The carriage 10 has an arm 11 extending forwardly above a cylindrical record 12 which is removably carried by a mandrel 13. Movement 25 of the carriage 10, longitudinally of the record 12, may be effected by a driving means comprising a feed screw 14 (see Figs. 1 and 3), which is rotatably supported by the above mentioned standards and with which there is brought into 30 engagement a feed nut 15 which is movably connected to the carriage in any suitable manner for movement into and out of engagement with the feed screw. When the feed nut is engaged with the feed screw, a steady rotation of the 35 latter will cause a steady progressive travel of the carriage across the record 12. Such a rotation of the feed screw 14, as well as a rotation of the mandrel 13, may be effected by any suitable motor not herein necessary to show.

40 The carriage arm 11 carries a translating device 16 shiftable from an inoperative condition into respective operative conditions for recording and reproducing. When the device is conditioned for recording, it is adapted to receive sound waves by way of a tubular element 19 on the translating device and impart a movement undulating in accordance with those waves to a recorder stylus 20, and when the device is conditioned for reproducing it is adapted to create

sound waves in accordance with the undulating movement imparted to a reproducer stylus 21 as it tracks a modulated groove in the record. The placing of the translating device into its respective conditions, as well as the placing of the feed nut 15 into and out of engagement with the feed screw 14, is controlled by a lever 22 pivoted, as at 23, to the right side of the carriage arm 11. The means by which the control lever effects its control functions need not herein be fully described. It is sufficient to state that its control action is effected through a rocking movement about the rod 8 of a block 25 which is coupled to the control lever through a link 24. This control action is such that when the control lever is in an upward position—the position it occupies in Figure 1—the translating device is conditioned for reproducing and the feed nut is held in engagement with the feed screw; that when the control lever is in a downward position, such as is indicated by dash-dot lines in Figure 1, the translating device is conditioned for recording and the feed nut is again held in engagement with the feed screw; but that when the control lever is in a neutral position intermediate its reproducing and recording positions the translating device is held in inoperative condition, wherein it is free of the record, and the feed nut is held out of engagement with the feed screw.

In order to operate a phonograph of the type described, the phonograph must be accessible at both its front and end portions, access to the front being necessary to manipulate the carriage 10 and the control lever 22, and access to the end being necessary to mount a record on the mandrel 13. Whenever a cabinet is made to fit closely to the phonograph, for the purpose of preserving space, it is highly desirable that the closure or cover also fit closely to the cabinet when the cover is in open position. To provide a cabinet closely fitting the phonograph and having a closure means which will open into a position wherein it closely fits the cabinet and yet renders the phonograph accessible at both its front and end portions, this closure means has been made into two separate closures, as has been aforementioned, there being one closure or cover at the front of the cabinet and another separate closure at the end or side of the cabinet. These closures are then interconnected so that both may be opened and closed by a single manipulation.

In a preferred form of cabinet, the upper portion is substantially arcuately shaped in cross section, as viewed from the end, and comprises a detachable rearward closure section 32 held in place in the manner disclosed in La Forest Patent No. 2,203,096 issued June 4, 1940, a forward closure or cover 33, and a movable side wall section or side closure 34. By having the upper portion of the cabinet arcuately shaped, sufficient accessibility may be provided to the front portion of the phonograph by the opening of the cover 33, which need not swing outwardly of the cabinet for opening movement but which may be pivotally mounted to swing upwardly within the rearward section 32. In such upward position, the cover 33 may conform closely to the walls of the rearward section 32 and thereby utilize very little of the interior space of the cabinet. The side closure 34 may be moved into an open position to provide access to the mandrel 13; in such open position the side closure

34 may conform closely to the walls of the cabinet and thereby also utilize very little of the interior space of the cabinet.

Since no access need be provided to the left side of the phonograph, the cover 33 may be pivoted leftwardly thereof in any suitable manner such, for example, as in the La Forest Patent No. 2,203,096 above mentioned. On the right side of the phonograph, however, there must be provided full access to the mandrel 13, and a form of pivotal mounting for the cover 33 must be used which will not interfere with such access to the mandrel. The cover 33 is therefore effectively pivoted by means of a sliding connection with the standard 7 of the phonograph. This sliding connection comprises an arcuately shaped member 35, formed as by stamping, made substantially equal to a half circle in length, and provided with a channelled portion 36 extending throughout the length thereof. In the channelled portion 36, longitudinally thereof, there is provided a slot 37. Passing through the slot 37 and threading into the standard 7 are the shoulder screws 38, the heads 38' of which are disposed for sliding movement within the channelled portion 36. Thus, the arcuate member 35 is supported by, and effectively pivoted to, the standard 7.

The forward portion of the arcuate member 35 is secured to the cover 33 by means of a small lug 39 turned up from the member 35, and by means of a narrow strip 40 bent over along the inner wall 36' of the channelled portion 36, the lug and forward portion 40' of the strip being each secured to the right-hand end wall 41 of the cover 33 at 39' as by spot-welding. The rearward portion of the strip is offset to the left along the line 42. With the above-described means, the cover 33 is effectively pivoted to the standard 7 without obstructing the free end of the mandrel 13.

In the present invention there is provided an operative interconnection between the cover 33 and side closure 34, to cause the side closure to be opened and closed by the opening and closing of the cover, which is positive and easy in its operation and very simple in its construction. In carrying out my invention the side closure 34 is pivoted to the front of the machine at a point away from the pivot axis of the cover 33, the side closure having a forward arm 43 which pivots, as at 45, to a lug 46 extending down from the front part of the base plate 3. While the side closure thus has a differently directed path of movement from that of the cover, yet it has always a component of its opening and closing movements directly in line or parallel with the opening and closing movements of the cover. This partial aligning of the movements of the cover and side closure permits them to be coupled simply through the medium of a sliding pivot. In the present instance this sliding pivot is placed between the end wall 41 of the cover and a rearward arm 44 of the side closure which terminates adjacent to the inner side of this end wall, and comprises a substantially radially extending slot 48 in the end wall 41 of the cover and a headed pin 47 on the end portion of the arm 44 which slidably engages this slot. As so arranged, when the cover 33 is swung upwardly into open position and downwardly into closed position, the side closure 34 is swung downwardly and upwardly into its open and closed positions, the pin 47 sliding radially inwardly and outwardly along the slot 48. Since the arm 44 terminates at the inner side of the end wall 41, the strip 40

of the arcuate member 35 is suitably offset along the line 42, as aforementioned, so that the arm will clear the arcuate member 35. Also, to permit the side closure 34 to be in substantial alignment with the end wall 41 of the cover 33, the arms 43 and 44 are suitably offset to the left at the lines 43' and 44' respectively.

Since the side closure 34 is connected continuously with the cover throughout the entire range of movement of the latter, the side closure is moved positively with the movement of the cover. Moreover, since the means connecting the cover with the side closure operates smoothly without any clashing of parts, the cover is easily movable between its open and closed positions. Such smooth and easy operation of the cover is highly desirable in a machine of the class herein described.

Although I have herein shown and described my invention in terms of a particular embodiment, it will be understood that this embodiment is subject to many changes and modifications without departure from the scope of my invention, which I undertake to express according to the following claims.

I claim:

1. In a cabinet of the class described: the combination of a pair of separate closures mounted on said cabinet for movement along differently directed paths between open and closed positions and having parallel motion components in their movements into open position and in their movements into closed position; members rigidly secured to said closures and having portions thereof adjacent to one another; and a sliding pivotal connection between said portions, causing one of said closures to be opened and closed concurrently with the opening and closing of the other.

2. In a cabinet for a phonograph: the combination of a pair of separate closures mounted on said cabinet for movement along differently directed paths between open and closed positions, said closures controlling access to different portions of the phonograph and having motion components in the same direction both in their movements into open position and into closed position; members rigidly secured to said closures and having portions adjacent to one another; and a sliding pivotal connection between said portions intercoupling said closures throughout their range of movement and causing one to be opened and closed by the opening and closing of the other.

3. In a cabinet for a phonograph: the combination of a movable closure on said cabinet controlling access to said phonograph from one side of the cabinet and having a portion at an adjoining side of the cabinet; a pivoted closure on said cabinet controlling access to the phonograph from said adjoining side; and a sliding pivotal means directly connecting said closure portion and said pivoted closure and causing one to open and close with the other.

4. In a cabinet of the class described: the combination of a first movable closure on said cabinet having portions at adjoining sides of the cabinet; a second movable closure at one of said adjoining sides of the cabinet arranged to abut with the respective portion of said first closure at said one side, at least one of said closures being pivotally mounted; and a direct sliding pivotal connection between said second closure and the said respective portion of said first clo-

sure causing said closures to open and close with one another.

5. In a cabinet for a phonograph: the combination of a pair of separate, pivoted closures on said cabinet having their pivot axes parallel but spaced from one another, said closures being adapted to swing in the same angular directions in their movements into open and closed positions, respectively; members respectively secured to said closures and in adjacent relationship with one another; and a sliding pivotal connection between said members causing said closures to open and close each with the opening and closing of the other.

15 6. In a cabinet of the class described: the combination of a cover mounted on said cabinet to move along a predetermined path to open and close the top of the cabinet and having an extension along a side of the cabinet; a closure pivoted to the cabinet at said one side thereof for movement along a path partially aligned with said predetermined path, said closure having a portion terminating adjacent to said extension; and a sliding pivotal connection between said extension and closure intercoupling said cover and closure throughout their range of movement and causing each to be opened and closed positively with the opening and closing of the other.

20 7. In a cabinet of the class described: the combination of a cover mounted on said cabinet for movement along a predetermined path into open and closed positions; a side wall closure on said cabinet pivoted at one end to swing along a path partially aligned with said predetermined path, into open and closed positions; an arm on said side closure; a side extension on said cover terminating adjacent to said arm; and means slidably connecting said arm with said side extension whereby to cause said cover and closure each to open and close with the other.

25 8. In a cabinet for a phonograph including a mandrel supported at one end and open at the other to receive a cylindrical record: the combination of a first closure on said cabinet pivoted for opening movement to expose the portion of the phonograph along said mandrel, said closure having a side extension terminating at the open end of the mandrel; a side closure adapted to abut with said side extension and pivoted to said cabinet on an axis removed from that of said first closure, said closures each swinging in the same angular directions about their respective axes in their opening movements and in their closing movements; and a sliding pivotal connection between said side closure and the side extension of said first closure causing said closures to open and close concurrently with one another.

30 9. In a cabinet of the class described: the combination of a closure mounted on said cabinet for movement along a predetermined path into open and closed positions; a second closure on said cabinet mounted to move into open and closed positions along a path partially aligned with said predetermined path, said closures having portions lying adjacent to one another of which one of said portions is provided with a slot running transverse to its path of movement; and a pivot on the other of said portions slidably engaging said slot.
